UNITED STATES PATENT OFFICE.

EDGAR J. GRISWOLD, OF NEW YORK, N. Y.

PHONOGRAPH.

1,211,573.

Specification of Letters Patent. Patented Jan. 9, 1917.

Application filed July 12, 1916. Serial No. 108,778.

To all whom it may concern:

Be it known that I, EDGAR J. GRISWOLD, a citizen of the United States, and a resident of the borough of Manhattan of the city of New York, county and State of New York, have invented certain new and useful Improvements in Phonographs, of which the following is a specification, reference being had to the accompanying drawings, which 10 form a part hereof.

This invention relates to improvements in phonographs.

The invention seeks to provide a novel and efficient shock absorber to relieve the 15 weight of the horn, tone-arm and sound-box of a phonograph when the same are lowered into operative position with respective to a sound record.

Referring to the accompanying drawings 20 in which the invention is illustrated, Figure 1 is a side elevation partly in section of a phonograph structure embodying the invention. Fig. 2 is a side elevation of the shock absorber. Fig. 3 is a plan view thereof. 25 Fig. 4 is a perspective view of the shock absorber in modified form.

Referring now to the particular structure shown in the drawings, 1 is the phonograph case or frame. It contains the horn 20 2, tone-arm 3 and sound-box 4, these parts being rigidly connected together so as to provide a unitary structure which may be termed the sound unit.

5 is the top partition of the case through 35 which passes the spindle 6 on which is mounted the turn table 7 carrying the sound record 8. Secured to the large end of the horn are brackets 9 and 10 which surround and are securely fixed to a spindle 11 by 40 means of set screws 12. The spindle is arranged to rotate in bearings in the partition 5 and in the bottom wall 13 of the case. For this purpose the lower end of the spindle has preferably a reduced portion 14 which 45 fits in an elongated recess 15. 16 is a hand operated key by means of which the spindle 11 and sound unit may be raised and lowered. These parts are shown in their elevated position in Fig. 1. When the key 16 50 is turned up, the spindle 11 and sound unit move to their lower position in which the needle of the sound box contacts with the record 8.

In a phonograph such as that shown in 55 the drawings, the sound unit and spindle weigh about nine pounds. It not infre-

quently happens that when the phonograph is to be operated and the key 16 is raised, the key slips from the hand or is raised too suddenly. The sound unit, therefore, drops to its lower position and causes the needle to strike the sound record with such violence that the sound-box, sound-record and, perhaps, other parts are injured. I, therefore, provide a shock absorber for the sound unit to prevent such injury to the parts. This shock absorber comprises two levers 17, 18 pivotally mounted on the fulcrum 19. The levers are engaged on one side of the fulcrum by suitable spring means to yieldingly hold apart the ends of the levers on the opposite side of the fulcrum. In the preferred arrangement, these spring means preferably consists of a split ring spring as shown in Fig. 4, or two of such split ring springs as shown in Figs. 2 and 3. As shown in Figs. 2 and 3 the lever 17 is composed of the arms 17^a and 17^b and the lever 18 is composed of similar arms. The split rings 20 and 21 have their ends in engagement with notches cut in the levers near the fulcrum 19 and on the short ends of the levers. The springs are normally under tension.

22 is a saddle plate connected with the arms 17^a and 17^b by pivots 23 and 24.

25 is a similar saddle plate connecting the arms of the lever 18. These saddle plates are on the opposite side of the fulcrum 19 from the springs 20 and 21. Each of the saddle plates is provided with an opening 26 which enables the spring support to be slipped into position, as shown in Fig. 1, wherein the reduced portion 14 of the spindle 11 passes through the opening of the saddle plates and the saddle plate 25 rests on the base 13 and the enlarged portion of the spindle 11 bears upon the saddle plate 22, so that the weight of the spindle and sound unit are carried by the spring support.

When the key 16 is turned down, as shown in Fig. 1, the weight of the spindle and of the sound unit are borne largely or entirely by the key 16. At this time the saddle plates 22 and 25 are separated from each other at the extreme limit of separation. When the key 16 is turned up, the weight of the spindle 11 and sound unit are brought to bear upon the shock absorber and the saddle plates 22 and 25 approach each other. As these saddle plates approach each other, the ends of the springs 20 and 21 separate

and the tension of the springs increases. This increased tension, however, is compensated for by the fact that the ends of the springs are necessarily brought nearer 5 to the normal line 27 passing through the fulcrum 19 so that the resistance of the shock absorber to the weight brought to bear upon it remains nearly uniform as the saddle plates 22 and 25 approach each other 10 under the weight of the sound unit and spindle 11.

In Fig. 4 the levers 28 and 29 are formed of metal strips whose ends remote from the split ring spring 30 are twisted through an 15 arc of 45° to provide saddles at these ends of the levers. In this form only one spring ring is used and pivoted saddles are obviated. This reduces the cost of manufacturing the device.

20 Heretofore, a coiled spring has been employed to take part of the weight of the sound unit, but such spring has been so arranged that its resistance to the weight of the sound unit rapidly increased when such 25 weight was brought to bear upon the spring. It was necessary to limit the maximum resistance of the spring in order that, when the full weight of the sound unit bore upon it, the needle might be in proper contact 30 with the sound record. As a result, the initial resistance of the spring was too small and when the key, such as the key 16, was suddenly released or slipped from the hand as often happened, the spring gave way entirely under the momentum of the falling 35 sound unit and the needle struck the sound record with such force as to injure the sound-box, sound-record and perhaps other parts. With the spring support above described, the resistance of the spring, in the preferred form of the support, is substantially uniform and its initial resistance to the weight of the sound unit is such that the sound unit cannot drop suddenly to its 40 lowest position. Hence, if the key 16 is suddenly released, no injury to the parts can occur. This is one of the important features of the invention herein described.

50 The shock absorber may be placed in any suitable position so as to take the weight of the sound unit.

What I claim is:

1. The combination with a phonograph horn of a shock absorber therefor comprising a pair of levers; a fulcrum on which the levers are pivoted; and spring means engaging the levers on one side of the fulcrum to yieldingly hold apart the ends of the levers on the opposite side of the fulcrum, the weight of the horn bearing upon said last mentioned ends of the levers.
2. The combination with a phonograph horn of a shock absorber therefor comprising a pair of levers; a fulcrum on which the levers are pivoted; and a split ring spring 65

engaging the levers on one side of the fulcrum to yieldingly hold apart the ends of the levers on the opposite side of the fulcrum, the weight of the horn bearing upon said last mentioned ends of the levers. 70

3. In a phonograph the combination of a sound unit comprising a sound-box, tone-arm and horn forming a unitary structure; a spindle mounted in bearings and to which the sound unit is attached; means for raising and lowering the spindle and sound unit; and a shock absorber for the spindle and sound unit comprising a pair of levers, a fulcrum on which the levers are pivoted, and spring means engaging the levers on 75 one side of the fulcrum to yieldingly hold apart the ends of the levers on the opposite side of the fulcrum; the weight of the spindle and sound unit bearing upon said last mentioned ends of the levers. 80

4. In a phonograph the combination of a sound unit comprising a sound-box, tone-arm and horn forming a unitary structure; a spindle mounted in bearings and to which the sound unit is attached; means for raising and lowering the spindle and sound unit; and a shock absorber for the spindle and sound unit comprising a pair of levers, a fulcrum on which the levers are pivoted, and a split ring spring engaging the levers on 85 one side of the fulcrum to yieldingly hold apart the ends of the levers on the opposite side of the fulcrum, the weight of the spindle and sound unit bearing upon said last mentioned ends of the levers. 90

5. The combination with a phonograph horn of a shock absorber therefor comprising a pair of levers; a fulcrum on which the levers are pivoted; and spring means engaging the levers on one side of the fulcrum to 95 yieldingly hold apart the ends of the levers on the opposite side of the fulcrum, the weight of the horn bearing upon said last mentioned ends of the levers and said spring means being so arranged as to offer a nearly uniform resistance to the weight of the horn. 100

6. The combination with a phonograph horn of a shock absorber therefor comprising a pair of levers; a fulcrum on which the levers are pivoted; and a split ring spring 105 engaging the levers on one side of the fulcrum to yieldingly hold apart the ends of the levers on the opposite side of the fulcrum, the weight of the horn bearing upon said last mentioned ends of the levers and said split ring spring being so arranged as 110 to offer a nearly uniform resistance to the weight of the horn. 120

7. In a phonograph the combination of a sound unit comprising a sound-box, tone-arm and horn forming a unitary structure; a spindle mounted in bearings and to which the sound unit is attached; means for raising and lowering the spindle and sound unit; and a shock absorber for the spindle and 125 130

- sound unit comprising a pair of levers, a fulcrum on which the levers are pivoted, and spring means engaging the levers on one side of the fulcrum to yieldingly hold apart 5 the ends of the levers on the opposite side of the fulcrum, the weight of the spindle and sound unit bearing upon said last mentioned ends of the levers, and said spring means being so arranged as to offer a nearly 10 uniform resistance to the weight of the sound unit and spindle.
8. In a phonograph the combination of a sound unit comprising a sound-box, tone-arm and horn forming a unitary structure; a 15 spindle mounted in bearings and to which the sound unit is attached; means for raising and lowering the spindle; and a shock absorber for the spindle and sound unit comprising a pair of levers, a fulcrum on which the levers are pivoted, and a split ring 20 spring engaging the levers on one side of the fulcrum to yieldingly hold apart the ends of the levers on the opposite side of the fulcrum, the weight of the spindle and sound unit bearing upon said last mentioned ends 25 of the levers, and said split ring spring being so arranged as to offer a nearly uniform resistance to the weight of the sound unit and spindle.

This specification signed this 11th day of 30 July, A. D. 1916.

EDGAR J. GRISWOLD.
